Primary Examiner — Derrick Holland*Assistant Examiner* — Lauren Calve(74) *Attorney, Agent, or Firm* — Altis & Wispro Law Group, Inc.(57) **CLAIM**

The ornamental design for an electronic reader, as shown and described.

DESCRIPTION

FIG. 1 is a perspective view of an electronic reader showing our design;

FIG. 2 is a front elevational view thereof; and,

FIG. 3 is a cross-sectional view thereof taken along lines III-III indicated in FIG. 2.

The broken line showing of an electronic reader represents unclaimed subject matter and forms no part of the claimed design.
